N. B. HURD.
CASEMENT WINDOW ADJUSTER.
APPLICATION FILED JULY 22, 1919.

1,323,595.

Patented Dec. 2, 1919.

WITNESS 14
C. Mitchell

UNITED STATES PATENT OFFICE.

NORMAN B. HURD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

CASEMENT-WINDOW ADJUSTER.

1,323,595.

Specification of Letters Patent.

Patented Dec. 2, 1919.

Application filed July 22, 1919. Serial No. 312,617.

To all whom it may concern:

Be it known that I, NORMAN B. HURD, a citizen of the United States of America, residing at New Britain, Connecticut, have 5 invented a new and useful Casement-Window Adjuster, of which the following is a specification.

My invention relates to a friction holding device for swinging sashes, blinds and the 10 like. The main object is to provide a very simple, comparatively inexpensive and yet efficient means for enabling one to open a sash window, or the like, to any desired extent in which position it will be frictionally held.

In the accompanying drawings:

Figure 1 is a plan view on a small scale illustrating my holder as it would appear in position.

20 Fig. 2 is a front elevation of the same.

Fig. 3 is a section on the plane of the line 3—3 of Fig. 1, the same being relatively enlarged.

Fig. 4 is a plan view of certain parts.

25 Fig. 5 is a plan view of a detail.

In the particular form of the invention shown herein, 1 represents a single bladed link. 2—2 represents the two blades of a double bladed link. The said links are 30 pivotally connected together at 3. The link 1 is pivotally connected at 4 to a plate 5 which may be screwed to the overhead stationary part 6 of a window frame or casing. 7 represents a hinged sash. Secured to the top

35 stile of the sash 7 is a bracket. This bracket comprises a back plate 8 from which projects forwardly a washer-like extension 9, which extension is preferably integral with the back 8. The blades 2—2 of the double 40 bladed link are washer shaped at their rear ends and enlarged to a size corresponding substantially to the washer-like extension 9. These two blades 2—2 rest respectively on top of and underneath the extension 9.

45 10—10 are washers which correspond substantially in size to the washer shaped ends of the blades 2—2. These washers 10—10 in turn rest against the blades 2—2 on the outside of the same. 11 is a bolt having a head 50 at one end and arranged to receive a threaded tension adjusting nut 12 at the other end. This bolt passes through the several washer shaped ends described as aforesaid so as to draw the several surfaces of the same into 55 frictional contact, the pressure depending

upon the degree to which the nut 12 is screwed down on the bolt 11. The shank of the bolt 11 is larger than the threaded end, as best seen in Figs. 3 and 4, and this shank is provided with one or more longitudinal grooves as indicated at 14—14, Fig. 4. The washers 10—10 are provided with lugs 10^a—10^a at their inner edges which project into the aforesaid grooves 14. The offset extension 9 is also provided with corresponding lugs, which take into the aforesaid grooves 14—14. Thus, when the link members 2—2 are turned, the bolt 11, the extension 9, and the washers 10—10 cannot turn with said link member 2—2, so that 70 the frictional binding of the surfaces of the several parts will be sufficient to cause the sash 7 to be retained at any angle at which it may be left when opened. In fact, the said device serves to frictionally hold the 75 sash in the closed position shown in the drawings. The back 8 of the bracket is, as shown in Fig. 2, preferably bowed so that the two screw-holes which receive the fastening screws indicated at 15—15 will stand 80 practically on a line with the offset member 9, thereby avoiding any twisting strain which would tend to draw out the screws. A lock nut may be provided if desired to hold the tension adjusting nut 12 in any desired 85 position of adjustment.

What I claim is:

1. In a device of the character described, a pair of pivotally connected links, one of said links comprising two spaced blades 90 having washer shaped ends, a bracket having a washer shaped extension, said two link blades standing above and below said washer shaped extension, friction washers arranged above and below the two members 95 of said link, means for drawing the surfaces of the several washer shaped parts into frictional binding contact, and means for preventing the independent rotation of said washers relatively to said washer 100 shaped extension while yet permitting the two blades of the double bladed link to turn between them.

2. In a device of the character described, a pair of pivotally connected links, one of said links including two washer shaped ends, a bracket having a washer shaped extension arranged to fit between the two ends of the last mentioned link, friction plates arranged above and below the washer like ends of 110

said link, means for locking said friction plates and said extension together against independent rotary movement while still permitting the two washer like ends of the 5 aforesaid link to turn therebetween, and means for pressing said several parts together to produce the desired frictional resistance between said parts to hold said link at different angles relatively to said 10 bracket.

3. In a device of the character described, a pair of pivotally connected links, one of said links comprising two spaced blades having washer shaped ends, a bracket having 15 a washer shaped extension, said two link blades standing above and below said washer shaped extension, friction washers arranged above and below the two members of said link, means for drawing the surfaces 20 of the several washer shaped parts into frictional binding contact, means for preventing the independent rotation of said washers relatively to said washer shaped extension while yet permitting the two blades of the 25 double bladed link to turn between them, said means comprising a bolt having a lon-

gitudinal groove in the side thereof, said extension and said washers each having a projection arranged to extend into said 30 groove.

4. In a device of the character described, a pair of pivotally connected links, one of said links comprising two spaced blades having washer shaped ends, a bracket having a washer shaped extension, said two link 35 blades standing above and below said washer shaped extension, friction washers arranged above and below the two members of said link, means for drawing the surfaces 40 of the several washer shaped parts into frictional binding contact, means for preventing the independent rotation of said washers relatively to said washer shaped extension while yet permitting the two blades of the 45 double bladed link to turn between them, said means comprising a bolt keyed to said extension and to said upper and lower washers with means for drawing the surfaces of the several washer shaped parts together comprising a nut threaded on said 50 bolt.

NORMAN B. HURD.
